HOSE SUPPORT

Allen M. Fellows, 15 Island Trail, Sparta, N.J. 07871

Filed Sept. 9, 1970, Ser. No. 24,898

Term of patent 14 years

Int. Cl. D6—99

U.S. Cl. D6—112

FIG. 1

FIG. 6

FIG. 2

FIG. 3

FIG. 5

FIG. 4

FIG. 1 is a side elevation of a hose support showing my new design;

FIG. 2 is a top plan view thereof;

FIG. 3 is a side elevational view thereof taken from the left-hand side of FIG. 1;

FIG. 4 is a side elevational view thereof taken from the right-hand side of FIG. 1;

FIG. 5 is a bottom plan view thereof; and

FIG. 6 is a view similar to FIG. 1 but of a second embodiment showing my new design.

I claim:

The design for a hose support, as shown and described.
